ELECTRODE FITTING

Stephen W. Borden, Summit, N. J.

Application November 2, 1936, Serial No. 108,817

9 Claims. (Cl. 247—1)

My present invention has for its object to produce a sturdy but relatively inexpensive fitting for connecting an electrical conductor and/or its protective covering, or two separate conductors to a ground pipe of relatively large size.

The various features of novelty whereby my invention is characterized will hereinafter be pointed out with particularity in the claims; but, for a full understanding of my invention and of its objects and advantages, reference may be had to the following detailed description taken in connection with the accompanying drawing wherein:

Fig. 1 is a cross section on line 1—1 of Fig. 3 and represents a fitting installed on a pipe and with a conductor and its protective covering in position in the fitting. Fig. 2 is a view at right angles to the water pipe and looking at the end where the conductor and its protective covering enter the fitting. Fig. 3 is a plan view and Fig. 4 is a section on line 4—4 of Fig. 3.

Referring to the drawing, 1 is a body member or yoke which is of somewhat greater length than the diameter of the largest pipe on which it is to be installed. 2—2 represent U bolts having threaded ends which pass through apertures in the body member or yoke. 3—3 are clamping plates for clamping the conductor or its protective covering to the yoke. These clamping plates have apertures aligned with the apertures in yoke 1 and through which the U bolts extend. 5—5 are threaded nuts on the U bolts and which, when tightened, clamp the conductor and/or its protective covering to the fitting and also clamp the fitting on the pipe. The portion of body member or yoke 1 lying between the clamping plates 3—3 is of channel formation as shown in Fig. 4. This formation permits the body member or yoke to be formed with a seat for the pipe as shown at 1 and in fact the bottom of the channel may be cut entirely away as shown by the dotted line 8, the yoke still having sufficient strength, because of the channel formation, to resist bending. The channel also serves to protect the conductor against mechanical injury or disturbance.

The yoke, directly beneath the clamping plates, is formed into seats for the reception of the conductor and its protective covering the seat for the conductor being shown at 10 and that for the protective covering at 10 it being of the same formation as seat 12. The plate 3 is invertible and one side is formed with a seat 11 for the conductor and the other side with a seat 12 for the conductor covering. In Fig. 2 the plate is

shown clamping the conductor covering while in Fig. 4 it is shown clamping the conductor.

Since U bolts suitable for any size of pipe are readily obtainable and inexpensive and since the only change necessary in the fitting to adapt it to pipes of practically any size is to increase the length of the yoke 1 this design is particularly advantageous for a fitting intended for the larger sizes of pipe. The construction of the clamps for the conductor and its covering which provides a clamping bolt at each side of the clamped member, adds greatly to the effectiveness of the clamp.

While the drawing shows a conductor with a protective covering, it will be clearly seen that a conductor without any protective covering may be attached with equal facility the conductor itself being preferably clamped under both clamping plates or each plate may clamp a separate conductor.

While I have illustrated and described with particularity only a single preferred form of my invention, I do not desire to be limited to the exact structural details thus illustrated and described; but, intend to cover all forms and arrangements which come within the definitions of my invention constituting the appended claims.

What I claim is:

1. A fitting for connecting an electrical conductor and its protective covering to a ground pipe which includes a pair of threaded U bolts spanning the pipe and spaced apart in parallel formation, a yoke for the U bolts the yoke having a pair of apertures in each end through which the legs of the U bolts pass, a pair of clamping plates each plate having two apertures aligned with the apertures in one end of the yoke and through each of which one leg of each of the U bolts passes; and a nut on each leg of each bolt and on the outside of the clamping plates for drawing the yoke against the pipe and each plate toward the yoke, for clamping to the yoke, by each plate selectively, a conductor or a conductor's protective covering selectively.

2. A fitting for connecting an electrical conductor and its protective covering to a ground pipe which includes a pair of threaded U bolts spanning the pipe and spaced apart in parallel formation, a yoke for the U bolts the yoke having a pair of apertures in each end through which the legs of the U bolts pass, a pair of clamping plates each plate having two apertures aligned with the apertures on one end of the yoke and through each of which one leg of each of the U bolts passes; and a nut on each leg of each bolt

- and on the outside of the clamping plates for drawing the yoke against the pipe and each plate toward the yoke, for clamping to the yoke, by each plate selectively, a conductor or a conductor protective covering selectively, and a seat for a conductor protective covering formed in the yoke substantially at right angles to the pipe and positioned between at least one pair of bolt apertures in the ends of the yoke.
10. 3. A fitting according to claim 2 characterized by the further fact that it includes a seat for a conductor positioned in the center of the seat for the protective covering.
4. A fitting for connecting an electrical conductor and its protective covering to a ground pipe which includes a pair of threaded U bolts spanning the pipe and spaced apart in parallel formation, a yoke for the U bolts the yoke having a pair of apertures in each end through which the legs of the U bolts pass and a seat for a conductor and a seat for a conductor protective covering positioned between each pair of apertures, a clamping plate having two apertures for the reception of corresponding ends of the U bolts 25 and a second plate having apertures for the other corresponding ends of the U bolts and a nut on each end of each bolt and on the outside of the clamping plates for clamping the conductor between one plate and the yoke and for clamping the protective covering between the other plate and the yoke and for clamping the yoke against the pipe.
5. In a fitting for connecting a grounding conductor and its protective covering to a ground pipe; a rigid metal member for contacting the pipe the member having portions extending beyond the pipe on opposite sides thereof said portions being substantially parallel and in the same plane and each of said portions having apertures, substantially at right angles to the plane of the portions, for the reception of at least two clamping bolts; bolts in the apertures and protruding therefrom in the direction away from the pipe, the bolts on one side of the pipe being attached to the bolts on the opposite side of the pipe by a member positioned against the pipe on the side opposite the rigid member; a conductor clamping plate positioned on the protruding portions of the bolts on one side of the pipe and a conductor protective covering clamping plate positioned on the protruding portions of the bolts on the opposite side of the pipe; and nuts on the bolts which when tightened clamp the conductor between one plate and the rigid member and clamp its protective covering between the other plate and the rigid member and clamp the rigid member on the pipe.
6. A fitting for connecting an electrical conductor to a ground pipe which includes a rigid body member abutting the pipe and extending beyond the pipe on each side thereof, a conductor clamping plate positioned above each extension, the portion of the body member lying between the plates being of channel formation for the reception of the conductor; together with means for fastening the rigid body member to the pipe and for clamping the conductor between the plates and the body member with the conductor in the channel.
7. A fitting for connecting an electrical conductor and its protective covering to a ground pipe which includes a rigid body member abutting the pipe and extending beyond the pipe on each side thereof, a first clamping plate positioned above the extension on one side of the pipe for clamping the conductor or its protective covering selectively to the body member and a second clamping plate positioned above the extension on the other side of the pipe for clamping the conductor or its protective covering selectively to the body member; means for clamping the body member to the pipe and for clamping the conductor between the first plate and the body member and for clamping the protective covering between the second plate and the body member.
8. A fitting for connecting an electrical conductor to a ground pipe which includes a pair of threaded U bolts spanning the pipe and spaced apart in parallel formation, a yoke for the U bolts the yoke having a pair of apertures in each end through which the legs of the U bolts pass, a clamping plate having two apertures aligned with the apertures in one end of the yoke and through each of which one leg of each of the U bolts passes and a nut on each leg of each of the four bolts and on the outside of the clamping plate for drawing the yoke against the pipe and the plate toward the yoke for clamping the conductor to the yoke.
9. In a fitting for connecting a conductor and its protective covering to a ground pipe; a clamp for the pipe which includes a body member for seating on top of the pipe and for the reception of the conductor and its covering, the body member having a projection at one side of the pipe and against which the conductor is to be clamped said projection having a pair of bolt holes spanning the conductor; and the body member having a projection on the other side of the pipe and against which the covering is to be clamped said latter projection having a pair of bolt holes spanning the covering; a conductor clamping plate for clamping the conductor to the body member the plate having a pair of bolt openings spanning the conductor and aligned with the bolt holes in the body member, a covering clamping plate for clamping the covering to the body member the covering plate having a pair of bolt holes spanning the covering and aligned with the bolt holes in the body member; threaded bolts positioned in the four bolt holes in the body member and extending through the aligned bolt holes in the clamping plates and means associated with the bolts, including nuts and a bolt interconnecting member positioned beneath the pipe, for clamping the body member to the pipe, to the conductor and to the conductor covering.

STEPHEN W. BORDEN.
